METHOD AND APPARATUS FOR REPLACING
WATER-COOLED ARCHESJohn S. Konrad, Leicester, Mass., assignor to The
American Steel and Wire Company of New
Jersey, a corporation of New Jersey

Application May 3, 1946, Serial No. 667,129

2 Claims. (Cl. 29—148)

1

This invention relates to a method and apparatus for replacing water cooled arches and more particularly to replacing an arch of the type shown in the copending application of Frederick H. Barnes, Serial No. 650,809, filed February 28, 1946. As disclosed in the said copending application, the water cooled arch is fastened to the inside of the buckstays of the furnace above the door opening. In some instances the welding of the water cooled arch is defective or may burn through and the arch must be replaced while the furnace is in operation. Previous to my invention it was necessary to permit the furnace to cool before replacing the arch, thus losing several hours operating time.

It is an object of my invention to provide a method of positioning a water cooled arch in a hot furnace.

Another object is to provide a positioning rig for use in carrying out the method.

These and other objects will be more apparent after referring to the following specification and attached drawings, in which:

Figure 1 is an elevation, partly in cross section, showing the positioning rig in two positions relative to the furnace;

Figure 2 is a top plan view of the positioning rig;

Figure 3 is an end view of the cradle of the positioning rig;

Figure 4 is a front view of the positioning rig; and

Figure 5 is a side elevation thereof.

Referring more particularly to the drawings, the reference numeral 2 indicates the vertical buckstays having a water cooled door frame 4 fastened thereto in the usual manner, the frame having a door opening 6 therein. A skewback channel 8 is fastened to the buckstays 2 above the door opening 6 and supports a skewback brick 10. The positioning rig consists of a column 12 having means near its bottom for receiving the ram 14 of a charging machine. A cradle 16 is pivotally mounted on top of the column 12 and supports a water cooled arch 18 which is provided with cooling water connections 20. Further details of the water cooled arch are shown in the copending application of Frederick H. Barnes, identified above.

As best shown in Figures 4 and 5, the column 12 is made from two vertical channel irons 22 having a plate 24 welded to their tops and a channel iron 26 extending therebetween and welded thereto some distance from their bottoms. Extending from the lower end of each of the chan-

2

nels 22 to the channel 26 are a pair of angle irons 28 which are spaced apart to provide grooves 30 shaped to engage the end of the charging machine ram 14. The cradle 16 is made of a bent plate 31 having vertical flanges 32 and 34 at its ends. Welded to plate 31 in spaced apart relationship are a pair of bars 36 which slope upwardly so as to support the arch 18 with its front wall in a substantially vertical plane. The plates 24 and 31 are provided with matching holes 38 and 40 for receiving a pivot pin 42 which extends downwardly therethrough and which is held in place by means of a cotter pin 44 extending through an opening therein.

15 The operation of the device is as follows:

The rig is placed on the end of the charging machine ram 14 with the cradle 16 turned so that its long dimension is perpendicular to the door opening 6. The ram 14 with the column

20 12 and cradle 16 mounted thereon is moved into the furnace through the door opening 6 and the cradle 16 is then turned through an angle of approximately 90°. The rig is raised to engage the burned-out water cooled arch and the water connections and mounting bolts are removed from the arch, after which the rig is lowered sufficiently to allow the rig and arch thereon to pass through the furnace opening. The cradle 16 is again turned 90° and removed from the furnace.

25 In some instances, especially in open hearth furnaces, the water connections and mounting bolts are removed and the burned-out arch shoved into the furnace where it is subsequently melted along with the charge of scrap. In replacing the arch the rig is supported on the ram 14 and a new arch 18 placed on the cradle 16 with its longitudinal axis perpendicular to the door opening as shown in full lines in Figure 1. The arch on the cradle is then moved through the door opening into the furnace, after which the cradle is turned through an angle of approxi-

30 mately 90°. The ram is then raised to move the arch into position, this being shown in broken lines in Figure 1. The arch 18 is then fastened to the buckstays 2 in the usual manner after which the ram 14 is lowered and the cradle 16 rotated through an angle of 90°. The rig is then removed from the furnace through the door opening 6.

35 While one embodiment of my invention has been shown and described, it will be apparent that other adaptations and modifications may be made without departing from the scope of the following claims.

I claim:

1. The method of positioning a water cooled

arch over the top of the door opening in a furnace which comprises supporting a column on the end of a charging machine ram, said column having a pivotally mounted cradle thereon, placing the arch on the cradle with its longitudinal axis substantially perpendicular to the door opening, moving the arch on the cradle through the door opening into the furnace, then turning the cradle with the arch mounted thereon through an angle of approximately ninety degrees in a substantially horizontal plane, and raising the ram to move the arch into position.

2. A rig for positioning water cooled arches and the like in a furnace, which rig comprises a column, means at the lower end of said column for receiving a charging machine ram or the like for carrying the rig, a cradle mounted on the top of said column for receiving said arch, the top of said cradle being shaped to support the arch with its front wall in a substantially vertical 20

plane, and means having a vertical axis for pivotally mounting said cradle on the top of said column to enable the cradle to move through an angle of approximately ninety degrees in a substantially horizontal plane only.

JOHN S. KONRAD.
